UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

HINGED-BOOK COVER

Application filed September 26, 1928, Serial No. 308,462. Renewed May 27, 1930.

This invention relates to book covers where-
in the back and sides are hinged together by
mechanical hinges. Such covers are useful
for heavy books such as ledgers, and for
5 loose-leaf books and for other purposes. The
present invention relates to the means for
fastening the hinge plates to the back and
sides. These hinge plates are metal plates
with their edges formed with hinge eyes,
10 those of the back alternating with those of
the sides, and united by the usual hinge pin
or pintle.

According to the present invention the
hinge plate for the back is embedded within
15 the material of the book back, with its hinge
eyes projecting at the edges thereof; and the
hinge plates for the sides are embedded in
the edge portions of the sides, which are
divided to form pockets receiving these hinge
20 plates and within which the plates are fast-
ened. The precise features which are charac-
teristic of the invention will be made appar-
ent in the course of the description.

Figure 1 of the accompanying drawings
25 is a transverse section of the back portion
of a loose-leaf book constructed according to
this invention.

Fig. 2 is an elevation of a portion of the
side of the cover partly broken away in sec-
tion.

Fig. 3 is an elevation of the inner side of
the book back, with the leather carrying the
hinge plate partly broken away to show the
latter.

Fig. 4 is a transverse section of a portion of
the cover side on a larger scale, on the line
4-4 in Fig. 2.

Fig. 5 is a similar transverse section on the
line 5-5 in Fig. 2.

Fig. 6 is a perspective view of one of the
hinge plates partly in section.

Fig. 7 is a transverse section of the book
back in process of formation.

Fig. 8 is a transverse section corresponding
45 to Fig. 5 but showing the parts before uniting
them.

Referring to the drawings, A is the
rounded back of the book and B, B are the
sides. These may be made of leather or of
50 any other suitable material, preferably a

leather-like material. In the description it
will be assumed that the material used is
leather.

In the back A is embedded a curved metal
55 plate C constituting both a stiffening plate
and a hinge plate; embedded in the inner edge
portion of the cover sides B, B, are hinge
plates D, D; the hinge plates C and D have
alternating hinge eyes c, d, united by wires
60 or pintles e in the usual manner. The plates
may be of a single thickness or two (or even
more) thicknesses of metal.

For applying the hinge plates D, D, to the
side boards B, B, the latter are slotted or
sawed into at their edges adjacent the hinge
joints, and the hinge plates D, D, are in-
65 serted into the slits or pockets thus formed
and are then fastened securely therein. Ac-
cording to the preferred construction the
hinge plate D is made, as shown in Fig. 6, of
70 a single plate which is bent upon itself to
form a double thickness where it is embedded
within the pocket in the leather side. The
sheet-metal between the hinge eyes d, d, is
75 utilized as a means for fastening the hinge
plate to the leather. For this purpose this
intervening portion, shown at f in Fig. 6, is
bent inward or backward, that is, in the con-
trary direction to the bending of the metal to
80 form the hinge eyes, and prior to the inser-
tion of the plate these portions f form pro-
jecting tongues or flanges on the opposite
sides of the hinge plate. When the hinge
plate is inserted in the pocket formed in the
85 leather, these tongues f come against the outer
edge of the leather, and then by placing the
cover side in a press they are driven down so
that the edges of the tongues are turned into
the material of the leather in the manner
90 shown in the cross-section Fig. 4. Thus the
edges of the tongues f are made to serve as
hooked flanges, whereby the plates are caused
to grip the leather firmly.

The plates D have also another means of
uniting them to the leather in the form of
95 spurs g, g (Fig. 6). These spurs are struck
up from the sheet metal at intervals, and
preferably adjacent the eyes d, so that they
engage the leather where it is not clamped by
the flanges f. These spurs are not turned
100

up perpendicularly, but stand at a slight angle, so that when the plate is introduced into the pocket and is then subjected to pressure from opposite sides, the spurs will enter into the leather and in so doing will be partially flattened down, so that they exert a stretching action upon the leather tending to draw it smooth and prevent any wrinkling.

By the fastening means described (either of which may be used without the other if desired, although their conjoint use is preferable), the plates D are securely fastened within the leather, and this without the use of any cementing material. Cements for uniting metal and leather are unsatisfactory in practice and are difficult and laborious to apply, and unless the work is done with great nicety the cement is liable to be smeared on the exterior. The present invention provides a means for fastening the plates to the leather by an instantaneous dry process. After inserting the plate in its place in the pocket, a single blow in a press is sufficient to complete the fastening of the parts together.

The leather flaps covering the inner or concave side of the back plate may advantageously be fastened down to that plate without the use of cement and by indenting spurs of metal similar to the spurs g already described. This is best shown in Fig. 3, where the spurs h are struck up from the metal of the back plate C. The spurs on opposite sides of the middle line are directed toward the middle so that as they are forced into the leather they bend away from each other and thereby draw upon and stretch or smooth the leather so as to avoid wrinkling. The spurs may be more or less numerous, as desired. This construction is advantageously applicable to those book backs wherein the leather is split from the inner side of the back in both directions so as to form flaps meeting or approaching along the middle; by lifting these flaps the curved back plate may be inserted beneath them; and by then striking the back between concave and convex dies in a suitable press, the leather flaps are forced down against the metal plate and the spurs of the leather are caused to penetrate the flaps, and in so doing are bent downward and toward the middle, as described.

The stretching operation of the spurs g and h will be understood by reference to Figs. 7 and 8 which show a single spur g or h in its original upturned position; under pressure the spur cuts completely into the leather above it, and as the pressure continues the spur is itself bent down, exerting a sort of swinging action around its attached portion whereby its free edge executes an arc-like movement as it penetrates the leather, so that finally it assumes an oblique position such as that illustrated in Fig. 1 or Fig. 5.

The application of spurs to the inner or concave side of the back plate for holding

down the inner flaps of the covering leather to the metal plate is claimed in a companion application executed by me to be filed approximately concurrently with the present application.

In Fig. 2 the plate D is shown with its ends curved at x. This is in order to fit the ends of the pocket in the leather when the leather is cut by a circular knife or saw, as is the preferred method. Making the plate with its rounded portion x to conform to the arc-shaped end of the pocket avoids the necessity of having to perform a special manipulation to enlarge the ends of the pockets to fit the plate, as would otherwise be necessary.

For a loose-leaf book it is customary to apply an inner back plate E (Fig. 1) against the inner face of the book back, to which to fasten the ring-binding mechanism or other loose-leaf binding devices which may be employed. It is customary to form the back plate C with ears, one of which is shown at i in Fig. 3, and in dotted lines at i in Fig. 1, these ears passing through slots in the inner plate and being then clinched down to fasten the inner plate to the back. Any suitable binding mechanisms, and any suitable means for fastening them to the back, may be provided, as special circumstances may require.

While the construction described is that preferred, yet it is to be understood that it may be greatly varied in matters of detail without departing from the essential features of the invention which are set forth in the appended claims.

What I claim is:

1. A hinged book cover comprising sides with metal hinge plates embedded therein, the sides formed with pockets opening along their inner edges, and the plates inserted into said pockets and having integral fastening means whereby they are fastened therein.

2. A hinged book cover comprising sides with metal hinge plates embedded therein, the sides formed with pockets opening along their inner edges, and the plates formed with integral portions engaging the marginal portions of the material of the sides to hold such material to the metal plates.

3. In a cover according to claim 2, the metal hinge plates formed with eyes, and with intervening tongues bent back and embracing between them the edge portion of the cover material.

4. In a cover according to claim 2, the hinge plates having spurs adapted under pressure to embed themselves in the edge portion of the material and draw it closely against the plates.

5. A hinged book cover comprising sides with metal hinge plates embedded therein, the sides formed with pockets and the plates having integral spurs pointing toward the open sides of the pockets; said spurs inclined and adapted under pressure to embed them-

selves in the material and draw it closely against the plates.

6. A hinged book cover comprising metal hinge plates embedded within the cover material, with alternated engaging hinge eyes 5 projecting beyond the edges of the material, and integral projections on said plates adapted under pressure to enter into the cover material and bind it closely to the metal hinge plates.
- 10 7. A book cover comprising a metal plate embedded within the cover material, the latter formed with a pocket having its end portions curved in substantially the arc of a circle, and the metal plate having its ends 15 correspondingly rounded to fit said pocket and fastened therein.

8. A hinged book cover comprising back and sides with metal hinge plates connecting them, at least one of such plates embedded 20 within the cover material and having integral spurs which under pressure enter the cover material and secure such material to the plate without resort to cement.

In witness whereof, I have hereunto signed
25 my name.

CLARENCE D. TRUSSELL.
